UNITED STATES PATENT OFFICE.

WILLIAM H. MINER, OF CHICAGO, ILLINOIS, ASSIGNOR TO W. H. MINER COMPANY, OF CHICAGO, ILLINOIS, A CORPORATION OF ILLINOIS.

RUNNING-BOARD SADDLE FOR CARS.

No. 891,354.

Specification of Letters Patent.

Patented June 23, 1908.

Application filed February 10, 1908. Serial No. 415,021.

To all whom it may concern:

Be it known that I, WILLIAM H. MINER, a citizen of the United States, residing in Chicago, in the county of Cook and State of Illinois, have invented a new and useful Improvement in Running-Board Saddles for Cars, of which the following is a specification.

My invention relates to improvements in the construction of running board saddles for cars, and more particularly to improvements upon the running board saddle heretofore patented to William E. Fowler, in Letters Patent of the United States No. 859,288 of July 9, 1907.

The invention consists in providing the base or bottom flange of the saddle, at its middle portion, with a slotted bolt opening furnished with an enlargement through which the head of the bolt may pass to enable the saddle to be conveniently applied to the car roof and securely bolted to the ridge pole, and thus prevent all danger of the saddle becoming loosened or displaced from the car and thereby endangering the train.

In the accompanying drawing, forming a part of this specification, Figure 1 is a perspective view of a running board saddle embodying my invention; Fig. 2 is a partial bottom plan view; Fig. 3 is a vertical cross section on line 3—3 of Fig. 2; Fig. 4 is a detail longitudinal section on line 4—4 of Fig. 2.

In the drawing A represents a portion of a car roof and B the ridge pole or central longitudinal member of the car roof frame.

D is the running board saddle, having a plurality of sockets d to receive the ends of the running board planks. The saddle D has a base or bottom flange D¹ shaped to fit the sloping sides of the roof at the peak or crown thereof, and furnished with ears or lugs d¹ having holes d² for reception of screws or bolts F to secure the same to the roof. The running board saddle D is also furnished with transverse division webs d³ separating the sockets d and with a longitudinal divi-

sion web d⁴ likewise separating the sockets d on the opposite sides of the saddle. At its middle portion, the saddle D is furnished with an oblong bolt opening or slot d⁵ having an enlargement d⁶, preferably of rectangular shape, through which the head G¹ of the bolt G may be inserted, which passes through the ridge pole B, and which serve to securely anchor the saddle to the car roof, so that there is no danger of its being loosened or disarranged.

In applying the saddle to the car roof the bolt G is first passed through the ridge pole or member B from the top, and then the running board saddle is applied, the head of the bolt being passed up through the enlargement d⁶; then the saddle is slipped lengthwise so that the bolt fits into the slot d⁵, thus causing its head G¹ to engage the base or bottom flange of the saddle on each side of said slot d⁵, then the nut G² of the bolt G is tightened, thus securing the saddle in place, afterwards the screws or bolts F may be inserted.

I claim:

1. A metallic running board saddle for car roofs having sockets to receive the ends of the running board planks, and a base or bottom flange adapted to fit the sloping sides of the roof at the peak or crown, and provided at its middle with a bolt slot furnished with an enlargement for the bolt head to pass through, substantially as specified.

2. In a car roof, the combination with the ridge pole of a car roof, of a running board saddle having sockets to receive the ends of the running board planks and furnished with a base or bottom flange provided with a bolt slot having an enlargement through which the bolt head may pass, and a bolt fitting in said slot and passing through said ridge pole to secure said saddle to the ridge pole, substantially as specified.

WILLIAM H. MINER.
